PETROLEUM AND GAS CONTROL APPARATUS

Application filed December 3, 1930. Serial No. 499,739.

This invention relates to apparatus for controlling gas-carrying petroleum under high pressure, particularly such gas-carrying petroleum as received directly from the wells, and the principal object of the invention is to step down the pressure while simultaneously chilling the fluid so that certain desirable gases will be retained within the liquid and certain gases which are undesirable in the liquid will be freed or conveyed to other uses. Another object is to provide automatically operated apparatus for effecting the above. Other objects will appear in the following description and accompanying drawing.

Crude petroleum as received from high pressure wells may run all the way to 1400 pounds or more to the square inch, and at various temperatures up to 180° F. or more depending on the locality and depth of the particular well, and such oils under high pressure and elevated temperature carry an enormous volume of gases, some of which such as butane, pentane and heavier gases, are desirable as constituents of commercial gasoline, while others of a more volatile nature such as ethane, propane, etc. generally known as fixed gases are undesirable, yet upon the free release of pressure of the petroleum as it issues from the well the desirable gases would be carried away with the undesirable gases, and to avoid this many forms of so-called gas traps have been devised, the chief object of which was to trap the liberated gases upon release of pressure so that the desirable gases and gasoline vapors could later be recovered. This recovery of the gasoline constituents of the gases was done either by compression and refrigeration or by absorption of the desirable gases from the undesirable gases by repeated contact with absorbing oils deficient in such gases.

It has also been the practice to expand off some of the lighter gases first from the oil, so that the succeeding gases removed were richer in desirable content so that the absorption treatment was more efficiently carried out.

Instead of following the above procedure,

we have discovered that the inherent pressure of the gas carrying oil may be made to induce auto-refrigeration of the fluid in successive steps and whereby the undesirable gases mentioned may be liberated while due to the drop in temperature the desirable gases are all recondensed within the liquid body and thus retained without resorting to the well-known steps of condensing and/or absorption, though, if desired, it is evident that these steps may be additionally practiced on any gas found carrying values in respect to richer gases which it is desired to recover.

To carry out the invention we have devised the apparatus shown in the drawing and in which Fig. 1 is a vertical central section of the apparatus, Fig. 2 is a cross section of Fig. 1 as seen from the line 2—2 thereof, Fig. 3 is an enlarged cross section of a fragment of the needle valve plate and adjacent portions, and Fig. 4 is a diagrammatic sketch of an installation of the devices.

In further detail, 1 is a vertically disposed heavy steel cylinder with outwardly curved heads 2, 3 preferably made of forged steel welded to the body of the tank at 4, 5, and the junctures covered by bands of steel 6, 7 shrunk in place and further welded to the body at their upper and lower edges as indicated, while extending through the reinforcing bands at opposite ends of the cylinder are inlet and outlet pipes 8 and 9 respectively.

Within the cylinder is an expansion pipe and slide valve assemblage all assembled and welded in place before welding on the cylinder heads. This assemblage comprises two heavy disks 10, 11 extending across and spaced inwardly from the opposite ends of the cylinder and firmly welded in place as indicated by the darker portions 12, while extending through these plates and firmly welded thereto at opposite ends is a plurality of pipes 13 arranged similarly to the tubes of a water tube boiler.

After welding the tubes and heads in place the upper end of the tube assemblage is turned off perfectly smooth and true and a flat smooth aperture and movable or slidable valve plate 14 is placed thereon and above

this is closely fitted another heavy disk 15 firmly welded to the cylinder and which disk is provided with a plurality of fine holes 16 each one of which is aligned over one of the bores of the tubes 13.

Plate 14 is likewise perforated with fine holes 17 which may be a trifle larger than holes 16 and are arranged to align with holes 16 in one position of the plate but which may, 10 by moving plate 14, be brought out of alignment with holes 16 so as to effectively close them off with respect to pipes 13 as shown clearly in Fig. 3. To permit movement of plate 14 and yet hold it to a proper path of 15 travel so as to bring its holes into alignment with holes 16, plate 14 is made somewhat smaller than the interior of the cylinder and is impinged at its opposite edges by hand screws 18 passing through stuffing boxes 19, 20 while a plurality of short pins 20 projecting from recesses in plate 10 and positioned in short slots 21 formed in plate 14 at points between its holes 17 function both as guide pins for disk 14 as well as supporting pins for 25 disk 15 so that the latter will not be forced down too tightly upon plate 14 to make it immovable under pressure.

The small holes 16 in plate 15 are outwardly beveled on their upper ends to form 30 tapered seats for a plurality of needle valves 22 projecting downwardly from a ribbed disk or needle valve head 23 carried at the lower end of a vertically extending rod 24 passing upward through cylinder head 2 and into a 35 small cylinder 25 where it is fitted with a piston 26 provided with rings 27 and a further extension or smaller piston 28 operating in a second small cylinder 29 against a compression spring 30, the force of which may be 40 adjusted by a screw 31 threadedly passing through the cap 32 of cylinder 29 and carrying upon its upper end a loosely splined gear 33 meshing in turn with a pinion 34 secured to the upper end of a shaft 35 operated by a 45 handwheel 36 secured to its lower end.

Cylinder assemblage 25-29 is bolted to a seat formed on top of head 2 and the lower part of piston 26 is exposed to pressure from 50 under cylinder head 2 through means of a small passage 37 which may be closed off more or less by a needle valve 38 adjustable from without by a handwheel 39.

Any fluid under pressure which might pass 55 piston 26 will find its way through into cylinder 29 for escape at vent 40, though when piston 26 is at its highest point its conical hub 41 seats in a complementarily formed depression in the upper end of cylinder 25 to seal off any possible leakage.

60 The space around the tubes between heads 10 and 11 is sealed from the spaces A and B at the ends of the cylinder and is provided with inlet and outlet fluid circulation pipes 42, 43.

65 Pressure gages 44, 45 are inserted in the

upper and lower ends of the cylinder as indicated, and at the extreme lower end is a sediment draw-off pipe 46, while on outlet pipe 9 is an automatic pressure regulating valve 46.

The entire vertical movement of needle valve head 23 is so limited that the tips of the valves 22 do not completely withdraw from their tapered seats, so as to insure against displacement of the valves relative to the apertures.

It should be noted that sliding valve plate 14 provides a dual control so that the flow may be modified or entirely shut off independent of and without altering the spring setting of 80 automatic expansion valves 22.

In operation, crude petroleum with its gas content under the pressure and heat from the well is admitted directly to the upper portion of the cylinder through pipe 8 until the pressure builds up to normal well pressure. This pressure acts upon the lower face of piston 26 and tends to raise the valves 22. However, spring 30 is then adjusted to counteract this pressure and permit a constant flow and expansion of the fluid through the small orifices and through the heat exchange tubes 13 to the space B at the lower end of the cylinder where a reduced pressure is maintained by the 90 automatic regulator 46.

The passage of the fluid through the small orifices breaks the oil and gas into a fine spray which in expanding falls downward through the tubes accompanied by a sharp drop in 100 temperature depending on the relative pressures, initial temperature and rate of flow permitted by the automatic control.

The oil and gas mixture is discharged from the lower chamber by means of the automatic 105 regulating valve 46 into the next of several succeeding pieces of similar apparatus as may be necessary to reduce the pressure to the desired point and the temperature to or below atmospheric.

With an oil-gas mixture from the well at 110 high pressure it is possible to obtain a great drop in temperature in the first apparatus, though on account of the moisture content of the oils there would be danger of freezing the 115 orifices, and it is better to drop the pressure several hundred pounds at a time in stages from one apparatus to the next with consequent progressive reduction of temperature, it being understood that succeeding devices should be proportioned to handle the increasing bulk of fluid passing therethrough, as indicated by the successive devices C, D, E, F in Fig. 4 followed by a gas separator G and pressure storage tank H.

120 It will be noted that pipes 42 and 43 will permit artificial cooling when required, particularly when treating oils under lower pressure and greater initial heat such as obtained from some stages of hydrogenating and cracking plants, or the circulation of a 130

warmer fluid to prevent undue cooling from too rapid an expansion from oils under high pressure and relatively low initial heat.

Summarizing the operations of the apparatus, and without burdening the specification with figures and technical data, it may be stated that an oil-gas mixture of from a 1000 to 2000 pounds pressure and at a temperature of about 180° F. may be expanded 5 through the apparatus to a pressure of 150 pounds and a temperature of 40° F., or forced by artificial means if necessary, with a result that all volatile fractions are condensed within the liquid up to and including butane, thus 10 allowing the objectionable or lighter dry gases to be separated off in any suitable separating chamber. If desired, a portion of the excess butane may be separated as a gas at a lower pressure. 15

When the oil is run to storage tanks and its temperature has gradually risen to atmosphere mean temperature say about 60° to 70° in average time, all of the condensed fractions of gasoline are retained down to 20 and including pentane (boiling point 97° F.) and a part of the butane (up to 5% by volume of total oil) is also retained. All gas and vapor should be separated in any convenient gas and oil separator or gas trap at 25 a pressure of 100 pounds per square inch or more as the butane will remain in a liquid state at temperature below 60° F. at this pressure. Any gas given off from a lower or atmospheric pressure tank will contain 30 high percentages of condensable vapor that may be saved by either the normal absorption or compression process and will not exceed perhaps one-hundredth part of the volume necessary to treat by a casing head plant. 35

From a consideration of the invention as disclosed it will be evident that minor changes may be made in the details of construction without departing from the mode of operation and scope of the appended 40 claims.

We claim:

1. Apparatus for controlling gas-carrying petroleum under pressure comprising high and low pressure chambers, a partition separating said chambers, a plurality of apertures through said partition, and dual means for separately controlling the openings of said apertures.

2. Apparatus for controlling gas-carrying petroleum under pressure comprising high and low pressure chambers, a partition separating said chambers, a plurality of apertures through said partition, valve means for simultaneously controlling the effective opening of the apertures, and a plurality of expansion tubes leading from said apertures to the low pressure chamber.

3. Apparatus for controlling gas-carrying petroleum under pressure comprising high and low pressure chambers, a partition sep-

arating said chambers, a plurality of apertures through said partition, valve means for simultaneously controlling the effective opening of the apertures, a plurality of expansion tubes leading from the apertures to the low pressure chamber, and means for circulating a heat exchange fluid around the outer sides of said tubes. 70

4. Apparatus for controlling gas-carrying petroleum under pressure comprising a cylinder, a transverse partition in said cylinder providing at opposite sides a high and a low pressure chamber and pierced by a plurality of apertures, a petroleum inlet to said high pressure chamber and a petroleum outlet from said low pressure chamber, a plurality of valves arranged for seating in said apertures respectively, a valve head to which said valves are secured, and means for moving said head to control the degree of opening of said apertures. 75

5. Apparatus for controlling gas-carrying petroleum under pressure comprising a cylinder, a transverse partition in said cylinder providing at opposite sides a high and a low pressure chamber and pierced by a plurality of apertures, a petroleum inlet to said high pressure chamber and a petroleum outlet from said low pressure chamber, a plurality of valves arranged for seating in said apertures respectively, a valve head to which said valves are secured, and means responsive to the pressure of said petroleum for moving said head to control the degree of opening of said apertures. 90

6. Apparatus for controlling gas-carrying petroleum under pressure comprising a cylinder, a transverse partition in said cylinder providing at opposite sides a high and a low pressure chamber and pierced by a plurality of apertures, a petroleum inlet to said high pressure chamber and a petroleum outlet from said low pressure chamber, a plurality of valves arranged for seating in said apertures respectively, a valve head to which said valves are secured, means for moving said head to control the degree of opening of said apertures, and a plurality of expansion tubes extending from said apertures to the low pressure chamber. 100

7. Apparatus for controlling gas-carrying petroleum under pressure comprising a cylinder, a transverse partition in said cylinder providing at opposite sides a high and a low pressure chamber and pierced by a plurality of apertures, a petroleum inlet to said high pressure chamber and a petroleum outlet from said low pressure chamber, a plurality of valves arranged for seating in said apertures respectively, a valve head to which said valves are secured, means for moving said head to control the degree of opening of said apertures, a plate arranged adjacent said partition and apertured to match the same, and means whereby the plate may be moved 110 115 120 125 130

to misalign its apertures with those of the partition.

8. Apparatus for controlling gas-carrying petroleum under pressure, comprising a cylinder, a transverse partition in said cylinder forming a high and a low pressure chamber at opposite ends of the cylinder, said partition having a plurality of apertures for passage of the petroleum from the one chamber to the other, a plurality of valves in the high pressure chamber seated respectively in said apertures, a head to which said valves are secured, a rod secured to said head provided with a piston, a cylinder in which said piston operates for simultaneously opening said valves, means for admitting pressure from the high pressure chamber to act against the said piston for opening said valves and adjustable means for counteracting the effect of said pressure against said piston.

9. In a construction as specified in claim 8, said means for admitting pressure from the high pressure chamber being manually adjustable to various values.

10. Apparatus for controlling gas-carrying petroleum under pressure, comprising a cylinder, a transverse partition in said cylinder forming a high and a low pressure chamber at opposite ends of the cylinder, said partition comprising a plurality of spaced tubes extending longitudinally of the cylinder secured at opposite ends to disks welded to the cylinder walls, a plate at one end of the tubes provided with a plurality of apertures aligned over the tube openings, and means for controlling the opening of said apertures.

11. Apparatus for controlling gas-carrying petroleum under pressure, comprising a cylinder, a transverse partition in said cylinder forming a high and a low pressure chamber at opposite ends of the cylinder, said partition comprising a plurality of spaced tubes extending longitudinally of the cylinder secured at opposite ends to disks welded to the cylinder walls, a plate at one end of the tubes provided with a plurality of apertures aligned over the tube openings, means for controlling the opening of said apertures, and means for circulating a heat exchange fluid around said tubes.

12. Apparatus for controlling gas-carrying petroleum under pressure comprising high and low pressure chambers, a plurality of tubular expansion passages separating the chambers, and a plurality of expansion valves in the high pressure chamber arranged for expanding a fluid from the high pressure chamber to the tubes.
